[57] CLAIM

The ornamental design for a solenoid cover, as shown and described.

DESCRIPTION

FIG. 1 is a top plan view of the solenoid cover showing my new design;

FIG. 2 is a front elevational view thereof;

FIG. 3 is a left side elevational view thereof;

FIG. 4 is a right side elevational view thereof; and

FIG. 5 is a rear elevational view thereof.

The solenoid is shown in broken lines for illustrative purposes only.

Fig. 1.Fig. 3.Fig. 2.Fig. 4.Fig. 5.
